COMBUSTION DEVICE

Olof Axel Ohlsson, Stockholm, Sweden

Application December 19, 1939, Serial No. 310,041
In Sweden May 17, 1939

6 Claims. (Cl. 110—31)

Hitherto it has been a difficult problem to burn solid high gas-yielding fuels such as coal, brown coal, peat, wood, chips or the like in an economical manner. Usually, small fireplaces are combined with a fuel magazine to facilitate the firing work but in arrangements of this kind it is difficult to control the distillation of the fuel so that the quantity of gas required for a predetermined quantity of heat corresponds to the supplied quantity of air. Owing to this fact relatively expensive low gas-yielding fuels such as coke are usually used for small magazine fireplaces. Again, in larger fireplaces it is difficult to achieve a good mixing of the combustible gases and the air so as to bring the combustion to an end within a reasonably large combustion chamber. These disadvantages have resulted in an actual need of improved combustion devices for solid high gas-yielding fuels.

The main object of the present invention is to bring about an improvement of this kind.

A further object of the invention is to effect a complete combustion and favourable working conditions by combining a gasification chamber generating producer gas and having a grate for the supply of air with a mixing and ignition chamber (or more such chambers) having an opening or more openings to the gasification chamber and serving to mix the gases with air and to ignite the mixture so that the final combustion is effected in a fire box or the like arranged after the mixing and ignition chamber.

A further object of the invention is to keep the height of the layer of the burning fuel approximately constant by providing for approximately constant distance between the grate and the upper portion of the gasification chamber in operation. To this purpose I prefer to arrange the mixing and ignition chamber wholly or partly in the gasification chamber or in direct communication therewith, for instance between the gasification chamber and the fuel magazine or in a pocket or the like, which communicates with the gasification chamber and which at least on one side is bounded by the fuel falling or sliding down into the gasification chamber.

A still further object of the invention is to keep the composition of the gases approximately constant. This result is gained by keeping constant the height of the burning fuel in the manner described and by providing for substantially constant supply of secondary air to the mixing and ignition chamber through one or more air inlets in or near to one end of the said chamber.

Still another object of the invention is to cause the pieces of fuel to fall or slide in a predetermined manner so as to form a free fuel surface close to the opening or openings of the mixing and ignition chamber in the gasification chamber by providing a constriction, shoulder, screen means or the like between the fuel magazine and the gasification chamber. The mixing and ignition chamber may be arranged in the mass of fuel in such a manner that it forms itself the said constriction or screen.

A further object of the invention is to effect an ejector action with accompanying vacuum of practically constant value in the mixing chamber and the gasification chamber.

Moreover, an object of the invention is to provide means for operating the combustion device intermittently at constant load and to facilitate the removal of ash.

Further objects and features of the invention will be described in the following specification with reference to the accompanying drawings, in which:

Figures 1 and 2 illustrate an embodiment of the invention in vertical sections, Figure 1 being taken transversally on the lines I—I in Figure 2, and Figure 2 being taken on the line II—II in Figure 1;

Figures 3 and 4 are similar sections of a further embodiment;

Figures 5 and 6 are similar sections of a further embodiment, Figure 5 being taken on the line V—V in Figure 6, and Figure 6 being taken on the line VI—VI in Figure 5;

Figures 7 and 8 are similar sections of a further embodiment;

Figures 9 and 10 are similar sections of a further embodiment, and

Figure 11 is a vertical section of still a further embodiment of the invention.

All figures are diagrammatical and merely show particulars with which the invention is concerned. In all figures the same reference characters indicate the same parts.

With reference to Figures 1 and 2 the fuel magazine 1 communicates with the gasification chamber 2 through constricted passages 3, 3 which in this case are located on both sides of the mixing and ignition chamber 4, which may be tubular preferably of a more or less cylindrical shape. The chamber 4 may be relatively narrow in relation to the chamber 2 and has one or more openings or slots 5 to the gasification chamber and one or more air inlets 6, preferably tapering towards its inner end and extending into

the interior of the chamber 4 longitudinally of the latter. At the bottom of the gasification chamber there are provided inclined grates 7 for the supply of primary air which is admitted through an adjustable valve 10. An ash door 9 may be provided for removal of ash. Below the grates 7 there may be provided a further grate 8 serving to separate ash and to allow the pieces of fuel falling down from the grates 7 to burn completely. The gasification chamber, the fuel magazine, the chamber 4 etc. may be provided with water jackets 11 communicating with some heating system. Preferably, the interior of the chamber 4 and the air inlet 6 is lined with refractory material.

Solid fuel filled into the magazine rests on the grates 7 so as to surround the tubular chamber, channel or duct 4 which screens the gasification chamber from a part of the fuel in the magazine. In the passages 3 on both sides of the chamber 4 the fuel falls or glides down forming free fuel surfaces adjacent to the opening or slot 5, which extends longitudinally of the chamber 4 and preferably has a relatively large width circumferentially of the chamber.

The air inlet 6 is connected to blower means indicated at 6a (say a fan) for injecting air under pressure into the inlet which in the embodiment shown is shaped so as to produce ejector action and consequently a vacuum of practically constant value in the chamber 4 and the gasification chamber 2 communicating therewith through the opening or slot 5.

In operation the supply of air to the grates 7 is adjusted so as to effect generation of producer gases in the gasification chamber 2. Due to the ejector action of the air entering the chamber 4 through the inlet or ejector 6 the producer gases generated from the fuel in the gasification chamber are drawn into the chamber 4, mixed intimately with the air from the inlet or ejector 6 and ignited. The supply of air through the inlet 6 is controlled in such a manner in relation to the production of gases and the supply of air through the grates, that the gas mixture forced at great velocity through the chamber 4 is not burnt completely within this chamber but the final and complete combustion of the mixture escaping at the end 12 of the chamber 4 takes place in a fire box or flame chamber diagrammatically indicated at F in Figure 2 and arranged directly after the chamber 4. A part of the air from the ejector 6 will sweep over the surface of the glowing fuel adjacent to the opening 5, thus activating the combustion and improving the mixing action.

According as the combustion proceeds new fuel glides down into the gasification chamber 2, and ash is separated through the space between the grates. It is very important that the surface of the grates and of the spaces therebetween is sufficiently large, i. e. relatively large in relation to the load of the grate so as to prevent formation of slag and to avoid ash and coke particles flying with the stream of gases through the layer of fuel.

As the height or thickness of the burning fuel layer is kept approximately constant due to the constant distance between the chamber 4 and the grates the producer gases have practically constant composition provided that the valve 10 and the ejector 6 supply a substantially constant quantity of air. The combustion proceeds very uniformly as the composition of the gases and also the draught is constant approximately. In

practice, the combustion is very similar to that of oil in an oil burner in that the incompletely burnt gases escaping at the end 12 of the chamber 4 are completely burnt with a bright flame in the flame chamber or fire box F.

A very suitable and economical operation is accomplished if the fireplace or combustion device described is constructed to operate intermittently at constant load during periods the duration of which is determined by the mean requirement of heat. During the stand-still periods the supply of air through the inlet 6 is closed and the supply of primary air through the valve 10 is restricted so as to maintain a very slow fire (glowing fuel). This control may be effected automatically through impulses acting in dependence of the temperature or the pressure in a heating system connected to the fireplace or the like. Often it may be favourable to admit the supply of air through the ejector 6 to the chamber 4 after the valve 10 is opened so that when it is intended to increase the heat from slow fire to maximal load, the supply of primary air to the grates is started earlier than the ejector 6, but when it is intended to decrease the heat maximal load to slow fire the supply of primary air is reduced or closed earlier than the ejector. Thus, in the former case the production of gas is initiated before the ejector is started whereby harmful excess of air in chamber 4 is avoided. On the other hand, the ejector will continue to work for some time after the primary air to the grates has been closed for slow fire so as to secure the supply of sufficient quantity of secondary air for the combustion of the gases in the chamber 4 as long as the fire still is hot. During the slow-fire periods it is only necessary to supply so much primary air to the grates that the fire barely is kept alive, while the fan for the air inlet 6 may be closed completely.

It is also possible to connect the fan 6a with the valve 10 so that the fan supplies air both to the ejector 6 and to the grates 7. For this case one or two valves may be arranged to control the supply of air to the ejector and to the grates respectively.

The arrangement according to Figures 3 and 4 differs from that shown in Figures 1 and 2 insofar as the constriction 3 is formed by the sloping walls 1a, 1a of the fuel magazine 1. The grates 7 are curved, for instance approximately semi-circular, and form together a basket-like grate opened at the top and the bottom. Preferably, the curved grate bars 7 are arranged to be adjusted, for instance by being swung around axes 7a, which may be operated from the outside of the fireplace so as to approach and separate the grate bars from one another. Under the influence of this action, which is effected with predetermined intervals of time, the fuel is prevented from catching in the gasification chamber 2, and ash and refuse of fuel may easily be removed. In this embodiment the chamber 4 is located in the interior of the basket-like grate 7.

In Figures 5 and 6 a portion (say the middle part) of the chamber 4 is arranged in a pocket 5b bounded on two sides by the walls 1b and 1c and on the third side by the free surface 5a of fuel which is caused to glide downwards at a predetermined angle due to the constriction 3 formed by the sloping wall 1d of the fuel magazine. At one end the pocket now described communicates with the inlet 6 and at the other end with the tubular chamber 4. Communication with the gasification chamber 2 is effected through the free

opening 5 bounded by the surface 5a. In this case only one grate 7 need be provided.

According to Figures 7 and 8 the constriction 3 is formed substantially in the same manner as in Figures 3 and 4. The fuel glides downwardly 6 and uncovers an annular chamber or a pocket 5c at the top of the gasification chamber 2. The chamber 5c communicates with the chamber 4 as shown in Figure 8. The air inlet 6 is arranged near the inner end of the chamber 4.

In the arrangement shown in Figures 9 and 10 the fuel glides downwardly through the restricted passages 3 and rests on the grate 7a, which in this case is arranged to rotate by means of a rotatable shaft 13 and a gear 13a. In operation the grate is rotated, whereby the refuse of fuel may be removed continuously by means of a scraper. The middle portion of the chamber 4 is constituted by a space bounded by walls 1e and the free surface of fuels exposed at the opening 5.

Also in Figure 11 the grate 7b is rotatable by means of a screw 13b and a worm wheel 13c rotating the shaft 1c. In this embodiment the air inlet 6 and a part of the chamber 4 is vertical and the constrictions 3 are formed between the latter chamber and the vertical walls 1f of the fuel magazine 1. The rotating shaft 1c of the grate is hollow and serves to supply air to the inlet 6. The inlet 6 and the chamber 4 may be arranged to incline in any other manner.

In all embodiments the constricted passages 3, should be dimensioned so as to prevent the fuel from getting caught.

Primarily the device described is intended to be used as an additional aggregate for boilers, particularly for central heating furnaces or the like, in which case the chamber 4 is connected to the fire box or the flame chamber of the boiler or the furnace, preferably similarly to an oil burner. If it is desired to use the device for old boilers merely a slight modification of the front plate of the boiler is necessary. The device according to the invention may be used for any high gas-yielding, solid fuel and may be adapted for any requirement of heat.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense. Thus it is not necessary to supply air under pressure to the air inlet 6 but the air may be drawn through this inlet and through the grates by means of a suction apparatus arranged in the chimney from the device. The air flowing through the air inlet may be divided into a plurality of small jets, for instance arranged coronarily.

What I claim is:

1. A combustion device comprising in combination means defining a fuel receptacle for solid fuel; means defining a gasification chamber to generate producer gas adjoining and below said fuel receptacle; means defining a constricted conduit interconnecting said fuel receptacle and gasification chamber and through which fuel passes from the former to the latter; a duct for the collection of producer gas from the gasification chamber and constituting the ignition chamber for such gases, said duct being arranged intermediate said fuel receptacle and gasification chamber and having a passageway interconnect-

ing said gasification chamber with the interior of said duct; supporting means in said gasification chamber, in part at least below said duct and on the side of the latter which is provided with said passageway, for supporting in said gasification chamber, between said supporting means and said passageway, fuel fed from said fuel receptacle through said constricted conduit; said duct having an exit opening at the rear end thereof and means at the front end thereof for injecting air under pressure into and through said duct, and said passageway being arranged intermediate the exit end and the front end of said duct.

2. A combustion device comprising in combination a casing defining a fuel receptacle for solid fuel and a gasification chamber, said chamber forming a continuation of the said fuel receptacle and being arranged therebelow, whereby fuel from the former may be fed to the latter; means for supplying primary air to the gasification chamber to generate producer gas therein; a duct defining a gas collecting and igniting chamber, said duct being arranged within said casing intermediate said fuel receptacle and said chamber, said duct having an air inlet at the front end thereof and an exit at the rear end thereof and a passageway interconnecting the interior thereof with the gasification chamber, said passageway being positioned intermediate said front and rear ends; supporting means in said gasification chamber, below said duct and on the side of the latter which is provided with said passageway, for supporting in said gasification chamber, between said supporting means and said passageway, fuel fed from said fuel receptacle; and means for injecting air under pressure to and longitudinally through said duct.

3. A combustion device comprising in combination means defining a fuel receptacle for solid fuel; means defining a gasification chamber to generate producer gas adjoining and below said fuel receptacle; means defining a constricted conduit interconnecting said fuel receptacle and gasification chamber and through which fuel passes from the former to the latter; a duct for the collection of producer gas from the gasification chamber and constituting the ignition chamber for such gases, said duct being arranged intermediate said fuel receptacle and gasification chamber and having a passageway interconnecting said gasification chamber with the interior of said duct; supporting means in said gasification chamber, below said duct and on the side of the latter which is provided with said passageway, for movably supporting in said gasification chamber, between said supporting means and said passageway, fuel fed from said fuel receptacle through said conduit; said duct having an exit opening at one end thereof and an air nozzle inlet at the opposite end thereof, and means to supply air at high velocity to the said air nozzle.

4. A combustion device comprising in combination means defining a fuel receptacle for solid fuel, means defining a gasification chamber to generate producer gas adjoining and below said fuel receptacle; means defining a conduit interconnecting said fuel receptacle and gasification chamber and through which fuel passes from the former to the latter; a substantially horizontal gas collecting duct arranged in said conduit intermediate the fuel receptacle and the gasification chamber so as to screen a part of the latter from the fuel in the said receptacle, said duct having an air inlet at one end thereof and an

exit opening at the opposite end thereof, an intermediate portion between the ends of the duct being open to the gasification chamber to collect gases therefrom; an upwardly and outwardly inclined supporting grate in said gasification chamber, below said duct and on the side of the intermediate opening thereof, for supporting in said gasification chamber, between said grate and said intermediate opening, fuel fed from said fuel receptacle; and jet means for supplying air under pressure to said air inlet.

5. A combustion device comprising in combination means defining a fuel receptacle for solid fuel, means defining a gasification chamber to generate producer gas adjoining and below said fuel receptacle; means defining a conduit interconnecting said fuel receptacle and gasification chamber and through which fuel passes from the former to the latter; a substantially horizontal gas collecting duct arranged in said conduit intermediate the fuel receptacle and the gasification chamber so as to screen a part of the latter from the fuel in the said receptacle, said duct having an air inlet at one end thereof and an exit opening at the opposite end thereof, an intermediate portion between the ends of the duct being open to the gasification chamber

to collect gases therefrom; upwardly and outwardly inclined supporting grates in said gasification chamber, below said duct and on the side of the intermediate opening thereof, for sup-

5 porting in said gasification chamber, between said grates and said intermediate opening, fuel fed from said fuel receptacle; and jet means for supplying air under pressure to said air inlet.

6. A combustion device comprising in combination means defining a fuel receptacle for solid fuel; means defining a gasification chamber adjoining and below said fuel receptacle; means defining a constricted conduit interconnecting said fuel receptacle and gasification chamber and through which fuel passes from the former to the latter; inclined supporting means in the lower part of said gasification chamber and in substantial alignment with said conduit, for supporting in said gasification chamber the fuel fed from said receptacle; an air inlet into said gasification chamber above the fuel on said supporting means, and an exhaust duct leading from said gasification chamber above the fuel on said supporting means at a point substantially opposite said air inlet; and means to supply air under pressure through said inlet.

OLOF AXEL OHLSSON.
